Primary Examiner — Ian Simmons*Assistant Examiner* — Charles Hanson*(74) Attorney, Agent, or Firm* — Chen Yoshimura LLP(57) **CLAIM**

The ornamental design for a double stroller, as shown and described.

DESCRIPTION

FIG. 1 is a front, top and right side perspective view of a double stroller showing our new design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof;
FIG. 7 is a bottom plan view thereof; and,
FIG. 8 is a front, top and right side perspective view thereof showing two car seats placed on the double stroller.
The broken lines in FIG. 7 illustrate features on the underside of various parts of the double stroller and do not form a part of the claimed design. The broken lines in FIG. 8 showing the car seats are for the purpose of illustrating environmental structure and form no part of the claimed design.
